UNITED STATES PATENT OFFICE.

ADOLPH A. YERKES, OF ELMIRA, NEW YORK, ASSIGNOR TO AMERICAN SALES BOOK COMPANY, LIMITED, OF TORONTO, ONTARIO, CANADA, A CORPORATION OF ONTARIO.

MANIFOLDING SALES-BOOK.

1,291,339.

Specification of Letters Patent. Patented Jan. 14, 1919.

Application filed April 19, 1917. Serial No. 163,122.

To all whom it may concern:

Be it known that I, ADOLPH A. YERKES, a citizen of the United States, residing at Elmira, in the county of Chemung and State 5 of New York, have invented certain new and useful Improvements in Manifolding Sales-Books, of which the following is a full, clear, and exact description, such as will enable others skilled in the art to which 10 it appertains to make and use the same.

This invention relates to manifolding devices, and with respect to its more specific features, to manifolding salesbooks.

An object of this invention is to provide 15 a salesbook in which a greater number of copies may be made of one portion of a record than of another portion, and more specifically, in which triplicate copies of portions of the record may be made and 20 duplicate copies of other portions of the record.

A further object of this invention is to provide a salesbook having a translucent, as a parchment, triplicate, for only a portion 25 of the record whereby only such portions of the record as it is desired to check are made in triplicate, other portions of said record being made only in duplicate.

A further object of the invention is to 30 provide a salesbook in which the essential portions of the record may be made in triplicate on a parchment paper without the necessity of employing a parchment paper the full size of the sales slip.

Other objects will be in part obvious and 35 in part pointed out hereinafter.

The invention accordingly consists in the features of construction, combinations of elements and arrangement of parts which will 40 be exemplified in the construction hereinafter set forth, and the scope of the application of which will be indicated in the following claims.

In the accompanying drawing forming 45 part of this specification, and wherein similar reference characters refer to similar parts throughout the several views,

Figure 1 is a perspective diagrammatic view of a book embodying this invention; 50 and

Fig. 2 is a side view showing the sheet arrangement.

In accordance with this invention there is 55 provided a pad 1 comprising a series of sheets bound together, as by staples 2, to a

suitable back 3. Operatively associated with the pad 1 is a suitable transfer sheet 4, in the present embodiment double faced, and the transfer sheet and pad are so arranged as to enable a multiple record to be made. 60 In the embodiment illustrated each of the sheets 1 is folded back upon itself to form two leaves 5 and 6, only one of which, as 6, is retained by the staples and the other leaf, as 5, being free except for its attachment to the sheet 6. The sheet of transfer material 4 is conveniently, in the type of book illustrated, bound integrally with the pad on top thereof, in position to be interposed between the leaves 5 and 6 of each set 70 successively. The leaves 5 and 6 are preferably provided with a weakened line, as a line of perforations 7, so that they may be torn from each other, and a second weakened line 8 is provided for the leaf 5 to enable it to be torn from the stub portion of the book. One or both of the leaves 5 and 6 may be provided with one or more weakened lines, as 9, to enable one portion of the sales slip to be separated from another portion, as it is desirable under many circumstances to send one portion of the slip to one department and another portion to another department. Certain portions of the record, as for example those concerning the 80 article sold and the price paid therefor, are of such importance that it is desirable to have a triplicate or auditing copy thereof, while other portions of said record, as for example, the address to which the goods are 85 to be sent, may not require an auditing copy. In order, therefore, to enable a triplicate copy to be made of a portion of the record, a suitable sheet as of parchment, as 10, may be operatively associated with the leaves 5 and 6 in such a manner as to have transferred thereto by the carbon sheet an impression of such portions of the sales record 90 as are desired. In the embodiment illustrated the parchment is attached, as by being pasted to the rear face of the sheet 5, but in order to enable a record to be made only of that portion of the record desired, the parchment is attached intermediate the ends 95 of the sheet 4, and lies between said ends. The attached end of the parchment sheet terminates at or adjacent the weakened line 9.

In printed sales slips it is customary to employ the upper portion of the sheet for 100

the name and address of the person to whom the goods are to be sent, and the lower portion of the sheet for the record of the goods sold and the price, and if desired, also, the 5 name and address of the person to whom the goods are charged. With a sales slip of this type it is not required that the name and address of the person to whom the goods are sent be made in triplicate, but it is desirable that the other items on the sales slip 10 shall be. By reason of the employment of a parchment sheet shorter than the original sheet, not only is the quantity of the parchment paper which is required reduced to 15 substantially one-half of what would otherwise be required, but furthermore the liability of the parchment sheet to get out of place is much reduced, owing to its shorter length, and the record on that portion of 20 the sheet, the back of which is not protected by the parchment, is made on both sides of the sheet, thereby making it difficult or impossible to alter that portion of the record, as for example, in order to cause the goods 25 to be sent to a different address.

Thus by the above described construction are accomplished, among others, the objects hereinbefore referred to.

As many changes could be made in the 30 above construction and many apparently widely different embodiments of this invention could be made without departing from the scope thereof, it is intended that all matter contained in the above description or 35 shown in the accompanying drawing shall be interpreted as illustrative and not in a limiting sense.

It is also to be understood that the language used in the following claims is intended to cover all of the generic and specific 40 features of the invention herein described and all statements of the scope of the invention, which, as a matter of language, might be said to fall therebetween.

45 Having described my invention, what I claim as new and desire to secure by Letters Patent is:

50 1. A manifolding device comprising, in combination, a folded sheet and transfer material associated therewith whereby an inscription on one leaf of the folded sheet will be transferred to the other leaf of said sheet, and a third sheet disposed between said leaves so as to receive impressions from said 55 transfer material, said third sheet being attached to one of said leaves between the opposite ends thereof and lying between said ends.

2. A manifolding device comprising, in

combination, a folded sheet and transfer 60 material associated therewith whereby an inscription on one leaf of the folded sheet will be transferred to the other leaf of said sheet, and a third sheet of translucent material disposed between said leaves so as to receive 65 impressions from said transfer material, said third sheet being attached to one of said leaves between the opposite ends thereof and lying between said ends.

3. A manifolding device comprising, in 70 combination, a folded sheet providing two superimposed leaves, a double faced transfer sheet adapted to transfer impressions from one leaf to the one therebeneath, a parchment sheet interposed between said leaves 75 opposite a portion only of the area thereof, attached to one of said leaves intermediate its ends and having its free end lying adjacent to and within the folding line of said first mentioned sheet.

80 4. A device of the character described comprising, in combination, a pad comprising a series of sheets bound together, each sheet being folded back upon itself to form two leaves, a transfer sheet operatively associated with said pad and adapted to be interposed between the leaves of each successive sheet, one of said leaves having a weakened line intermediate its ends to permit said leaf to be separated into two portions, 85 and a triplicate leaf underlying one of said portions whereby a duplicate record may be made of inscriptions on one of said portions and a triplicate record of inscriptions 90 on the other portion.

95 5. A device of the character described comprising, in combination, a pad comprising a series of sheets bound together, each sheet being folded back upon itself to form two leaves, a transfer sheet operatively associated with said pad and adapted to be interposed between the leaves of each successive sheet, one of said leaves having a weakened line intermediate its ends to permit said leaf to be separated into two portions, 100 and a triplicate sheet attached to said leaf and terminating adjacent said weakened line whereby a duplicate record may be made of inscriptions on one of said portions and a triplicate record of inscriptions on the other 110 portion.

In testimony whereof I affix my signature, in the presence of two witnesses.

ADOLPH A. YERKES.
